UNITED STATES PATENT OFFICE.

HEINRICH KOPPERS, OF ESSEN, GERMANY, ASSIGNOR TO H. KOPPERS COMPANY, OF CHICAGO, ILLINOIS, A CORPORATION.

CLOSING MEANS FOR OVENS.

1,080,916.

Specification of Letters Patent.

Patented Dec. 9, 1913.

Application filed April 26, 1910. Serial No. 557,676.

To all whom it may concern:

Be it known that I, HEINRICH KOPPERS, engineer, residing at Isenbergstrasse 30, Essen, Germany, have invented a certain new and useful Improved Closing Means for Ovens, of which the following is a specification.

This invention relates to closing means for ovens, its object being to provide an efficient substitute for winches and jacks which travel along the roof of the oven-battery, over the doors, for the purpose of hoisting and opening same. These winches and jacks have the disadvantage that they, and the men working them, are exposed to risk of falling from the ovens, and also to the action of gas and vapors which are highly inconvenient to inhale, and in course of time injurious to metal. Moreover, the presence of the tracks at front and rear of the roof renders it necessary to place the mains between them, and the available space on the roof is thus considerably restricted. The present invention obviates these disadvantages, and primarily consists in removing and replacing the doors by means of a hoisting and traversing jack which is moved on a carriage in front of the doors, and has means for engaging the doors. By means of this jack the door is engaged, hoisted and eased, and then withdrawn by traversing the jack on the carriage, which can then be moved along the track to expose the door-aperture. With a traveling jack of this kind there is less liability to tilting, and the workmen are less exposed to the gases. On the push-engine side of the oven-battery the jack may be mounted on the same carriage with the push-engine. On the coke-bench side the carriage may carry a platform extending across the track, to serve as a bridge for the expelled coke, guide-walls being erected at the sides of the platform, across the carriage. Or to obviate the necessity for this or an equivalent bridge, and for sinking the track below the floor level, the carriage on the coke-bench side may travel on an elevated track, with the jack depending in front of the doors. The main or mains may be mounted on the frame-work on which the track is laid, clear of the roof.

Two constructions embodying the arrangements described are shown in the annexed drawings, in Figures 1 and 2, and 3 and 4 respectively, Fig. 1 being a front

elevation, Fig. 2 a vertical cross section, Fig. 3 likewise a vertical cross-section, and Fig. 4 a front elevation.

Like reference letters denote like or equivalent parts throughout the drawings.

Referring in the first place to Figs. 1 and 2, the horizontal coking chambers or ovens, marked *a*, have vertical front bars *b* forming parts of a frame-work *c*, on which are laid rails *e* running along the battery of ovens on the coke bench side, below the level of the oven floors. A carriage *f* driven by a motor *g* runs on the rails, and carries a hoisting jack *h* on guides on which the jack can be reciprocated by means of a screw *i*, suitable gear being provided enabling the screw to be coupled with the motor. The lifting member *l* of the jack is slideable in vertical guide-slots *k*, and is operated by means of a crank and toothed gear *m*. The member *l* has dogs *n* arranged in a common vertical plane and adapted to enter sockets *o* provided on the face of the iron structure *p* of the oven doors *d*. The carriage also has a platform *q*, forming a kind of bridge across the track, and a high wall *r* extending across the carriage is erected at each side of this platform. This platform extends over the track in front of the open oven, and permits the coke to be readily pushed out of the latter over the track and without spreading to the jack. For opening an oven the carriage is run in front of same, so that the jack is opposite the door, and the jack is then first reciprocated, to place the dogs *n* under the sockets *o*, secondly operated to slightly raise and ease the door, and, then traversed to remove the door from the frame. The carriage, carrying the door, is then moved along the track so that the platform *q* is placed opposite the open door-aperture, and the platform, on to the inclined quenching floor *s*. For re-inserting the door, the movements of the carriage and jack are reversed. It will be seen that by arranging a plurality of lifting dogs in a common vertical plane, the door will be positively and permanently maintained in a vertical position and in true parallelism with the door frame while being removed from or inserted into the latter in a direction parallel to the longitudinal axis of the coking chamber, so that any edging and jamming of the door more particularly previously to becoming properly seated within its frame is effec-

tively prevented. The absence of door hoisting mechanism on the top of the ovens, above the doors, enables the gas main *t* to be mounted on the frame adjacent the edge of 5 the roof, the ascension pipes *u* being bent over to join the main. Practically the entire roof is thus clear for charging purposes.

In the modification shown in Figs. 3 and 10 the frame *c* supports in addition to the main *t* an auxiliary main *v*, to which connection can be made by means of a pipe *x* carried by a tackle traveling on a rail *w*. The carriage *f* is in this case mounted on an elevated track *e*, in the manner of a traveling crane, and the jack *h* depends from the carriage, on which it can be reciprocated by 15 means of the motor *g*. The jack is in this case operated from the ground, its function being similar to that described with reference to Figs. 1 and 2.

What I claim as my invention and desire to secure by Letters Patent of the United States is:—

1. A device of the character described, 25 comprising an oven having a plurality of horizontal coking chambers, door frames at the mouths of said chambers, doors fitted into said frames and provided at their front with engaging means, a lifter adapted to travel in front of said doors and provided 30 with means adapted to successively coöperate with the engaging means of the doors, said engaging means and means on the lifter being so constituted as to prevent a tilting 35 movement of the door on the lifter, movable means for supporting the lifter which means are so constituted as to prevent a tilting

movement of the lifter relatively to the door frames, means for retracting the lifter on the supporting means to withdraw the door 40 from the frame, and means for moving the supporting means together with the lifter and door sidewise to expose the mouth of the opened coking chamber.

2. A device of the character described, 45 comprising an oven having a plurality of horizontal coking chambers, door frames at the mouths of said chambers, doors fitted into said frames and provided at their front with engaging means, a lifter adapted to travel in front of said doors and provided 50 with means adapted to successively coöperate with the engaging means of the doors, said engaging means and means on the lifter being so constituted as to prevent a tilting 55 movement of the door on the lifter, movable means for supporting the lifter which means are so constituted as to prevent a tilting movement of the lifter relatively to the door frames, means for raising the lifter on said 60 supporting means to ease a lifter-engaged door within its frame, means for retracting the lifter on the supporting means to withdraw the eased door from the frame, and means for moving the supporting means together with the lifter and door sidewise to expose the mouth of the opened coking chamber.

Signed by me at Barmen, Germany, this 13th day of April 1910.

HEINRICH KOPPERS. [L. S.]
